Primary Examiner — Eric Goodman*Assistant Examiner* — Bao-Yen Nguyen(74) *Attorney, Agent, or Firm* — Downs Rachlin Martin PLLC(57) **CLAIM**

The ornamental design for a snap in mount for linear extrusion profile, as shown and described.

DESCRIPTION

FIG. 1 is a perspective view of a snap in mount for linear extrusion profile showing my new design;

FIG. 2 is a front view thereof;

FIG. 3 is a first side view thereof;

FIG. 4 is a second, opposing side view thereof;

FIG. 5 is a top side view thereof; and,

FIG. 6 is a bottom side view thereof.

The broken lines in the Figures are for the purpose of illustrating unclaimed portions of the snap in mount for linear extrusion profile and form no part of the claimed design.
